UNITED STATES PATENT OFFICE

2,464,363

TRENCH CONSTRUCTION

De Witt H. Wyatt, Columbus, Ohio

Application September 7, 1945, Serial No. 614,963

3 Claims. (Cl. 138—81)

1

This invention relates to trench construction and is particularly directed to the provision of an improved trench for receiving pipes or conduits employed in transmitting heated and other fluids.

It is an object of the invention to provide an improved trench construction for the reception of steam-receiving pipes or the like, and wherein provision is made for supporting said pipes, and insulating the same against heat loss, when in underground positions.

It is another object of the invention to provide improved means for insulating and protecting industrial and central heating pipe systems or conduits that is simple to install, low in cost and of long operating life.

A further object is to provide a pipe-receiving trench composed of a plurality of tile blocks formed with longitudinally extending channels for the reception of pipes or conduits, suspension devices being carried by said blocks and arranged within the channels thereof for effecting the support of one or more pipes within said channels in spaced relation from the walls of the latter, whereby with the pipes so supported loose bulk insulating materials are receivable within the channels to completely surround the pipe or pipes arranged therein, whereby to minimize loss in temperature of heated fluids passed through said pipes.

For a further understanding of the invention, and additional objects and advantages thereof, reference is to be had to the following description and the accompanying drawings, wherein:

Fig. 1 is a perspective view, partly in vertical section, of an insulating pipe-receiving trench formed in accordance with the present invention;

Fig. 2 is a vertical transverse sectional view taken through the same;

Fig. 3 is a similar view of a modified form.

Referring more particularly to the drawings, the numeral 5 designates, in their entirety, vitrified clay trench blocks which form the major elements of the present invention. These blocks are adapted to be positioned in abutting longitudinally aligned order in a soil trench 6, or the blocks may be positioned on the soil and beneath the flooring of a building. The adjoining ends of the blocks may be united, as at 7, by means of mortar, adhesive tape, or placed merely in end to end abutting relationship. The blocks are formed internally so that they may be produced by standard stiff clay extrusion machinery.

In vertical cross section, as shown in Fig. 2 particularly, each block is of rectangular outline, having vertical side walls 8, a bottom wall 9 and

2

internal reinforcing ribs 10, all of integral construction. The internal ribs are shaped to produce a longitudinally extending, open-ended pipe-receiving chamber 11, which opens to the top of the block and is coextensive with the length of the latter. Below the chamber 11, there is provided by the ribs 10, a parallel drain passage 13 for the reception of moisture from the chamber 11, one of the lower horizontal ribs of the block being formed with openings 14 providing communication between the chamber 11 and the passage 13. The weight of the block is lightened by providing longitudinally extending openings 15 between the walls 8 and 9 and the ribs 10, although, if desired, the openings 15 may be used for the reception of electrical cables or the like.

The top of each block is longitudinally recessed as at 16 and, at longitudinally spaced intervals, vertical slots 17 communicate with the recesses. In order to support pipe members, shown at 18, within the longitudinally registering chambers or channels 11 of the blocks, use is made of a plurality of spaced stirrup-type hangers or straps 19. The ends of each of these hangers or straps are laterally bent as at 20 for engagement with the horizontal surfaces of the recesses 16 and then downwardly bent as at 21 for reception in the slots 17. The hangers may be of different lengths or heights so that two or more pipe members may be supported in parallel vertical order within the chamber of each block.

The construction of the hangers takes care of pipe expansion and contraction in a simple and efficient manner and, moreover, eliminates the need for expensive roller-type supports. It will be understood that the hangers may be either round or flat in transverse cross section. Through the use of the hangers, the pipe members are spaced from the inner walls of the chamber 11, providing space for the reception of a bulk, loose-fill or other form of thermal insulation, so that the construction will be thoroughly efficient in the transmission of heated or refrigerated fluids.

The open upper ends of the pipe-receiving chambers 11 of said blocks are closed by means of semicircular cover tiles 22, the latter being coextensive with the length of each block and the lower longitudinal edges thereof rest upon the horizontal surfaces of the recesses 16. One or more of these cover tiles may be formed with vertical extensions 23 for the reception of vertical pipes or valve stems communicating with the horizontal pipe members 18. Also, the extensions 23 may be used as vents for the escape of confined gases which may be present in the chambers 11.

A trench thus formed provides a completely satisfactory method or means for laying high or low pressure power and heating lines and pipe for the transmission of steam, water, oil, refrigerants or other liquids in locations disposed underground, outdoors, beneath factory floors and walls, and in all other locations where insulated conduits are needed. The vent channels 23 in the cover tiles permit free escape of vapors, and the drainage channels 13, in the bottoms of said blocks, prevent any accumulation of liquid. The blocks may also be laid to prevent moisture infiltration therein, so that the side openings 15 may be used, if desired, for communication and other electrical lines. Each block possesses a high insulating value aside from the insulation placed therein, thus further assisting in reducing heat losses. Also, the blocks are formed to possess high structural strength in order to avoid damage thereto from superimposed or extraneous loads. Another important advantage is to be found in the fact that the pipe members to be installed may be fitted together on the ground and lowered into the blocks after assembly thereof.

The invention is, of course, subject to certain modification without departure from its essential features of construction. Thus, as shown in Fig. 3, a ceramic enclosure for supporting underground pipe members is produced by forming said enclosure to consist of a pair of spaced longitudinally extending side tiles 24, a separate bottom tile 25 and a similar top tile 26. The meeting surfaces of these tiles are longitudinally grooved, as at 27, for the reception of mortar, cement, bituminous compounds or other similar bonding and sealing agents. Other variations will be apparent to those skilled in the art and, therefore, I reserve the right to employ all such modifications that may be said to fall fairly within the scope of the following claims. For example, while I prefer to form the trench blocks from extruded fired clay bodies, it is obvious that I may use other equivalent materials, such as cement or concrete, in the manufacture thereof.

I claim:

1. A conduit-receiving trench block, comprising an integral cellular body having an internal longitudinally extending conduit-receiving chamber, the latter being open to the top of the block, conduit-supporting stirrups positioned in said

chamber, said stirrups having hook-shaped upper ends receivable in slots provided in the upper portions of said block contiguous to the chamber, and a separable cover member positionable on the top 5 of said block to enclose said chamber and its contents.

2. A conduit-receiving trench block, comprising an integral cellular body having an internal longitudinally extending conduit-receiving chamber, 10 the latter being open to the top of the block, conduit-supporting stirrups positioned in said chamber, said stirrups having hook-shaped upper ends receivable in slots provided in the upper portions of said block contiguous to the chamber, a separable cover member positionable on the top of 15 said block to enclose said chamber and its contents, and a mass of heat insulating material disposed in said chamber to surround a conduit supported in the chamber by said stirrups.
3. A ceramic conduit-receiving trench block, 20 comprising a tile body substantially rectangular in its transverse cross-sectional configuration, said body being formed to include spaced inner and outer walls united by integral ribs, said inner 25 walls defining an internal open-topped conduit-receiving chamber having spaced upper edges, stirrups engaged with said upper edges and depending within said chamber to support entirely within the confines of the latter one or more conduits in spaced relation from said inner walls, and a mass of heat-insulating material disposed 30 in said chamber to completely surround a conduit.
